UNITED STATES PATENT OFFICE.

LESTER L. LASHER, OF BEACHMONT, MASSACHUSETTS, ASSIGNOR TO LASHER-PEER-BLOW COMPANY, OF BOSTON, MASSACHUSETTS, A CORPORATION OF MASSACHUSETTS.

BLOWTORCH.

Application filed March 12, 1926. Serial No. 94,351.

In the development of the blow torch, the wick as the important service element of the torch has been the subject of considerable study and thought, and various types of wicks and wick mountings have been devised in the effort to obtain a construction which would satisfactorily meet all of the requirements imposed in the manufacture, assembly and use of the torch.

10 In one type which has found favor in the trade, the wick is constructed as a relatively short, permeable plug which is press-fitted into the upper end of the torch barrel, and is centrally pierced to permit a separate and distinct piece of absorbent material, known as a "leader" to be threaded therethrough. With this type of wick, the problem of assembly is difficult. Special fixtures are required for press-fitting the plug into the barrel and for threading the leader through the plug, and such fixtures are not only expensive, but require workmen skilled in their use, thus adding considerably to the manufacturing cost of the torch, as well as making it practically impossible for the average torch user to replace a spent wick. Moreover, the tendency of the plug is to disintegrate upon removal, and inasmuch as the lodgment of the plug in the torch barrel is a press-fit, this very tightness of fit makes removal for purposes of replacement quite difficult.

To the end, therefore, of providing a wick unit and method of removably mounting the same within a torch barrel which will overcome the objections to existing types, I have devised my present invention.

According to my invention, the wick unit comprises a wick mounting constructed and arranged for quick attachable and detachable connection with the torch barrel, and a wick removably carried by said mounting. By this construction, I avoid the necessity for press-fitting the wick in the torch barrel, as in the case of the plug wick, with resultant economy in manufacturing cost, as well as convenience of removal and replacement of spent wicks.

The wick, itself, may be a straight length

of absorbent wicking material which is compressively but removably lodged within the wick mounting, such compressive lodgment effectively preventing leakage of the fuel therewith, and the exposed end of the wick constituting the flame area or "plug", from which the remainder of the wick extends as a "leader" for feeding the fuel thereto. My wick, therefore, retains all of the advantages of the old-style plug wick while avoiding the difficulties incidental to assembly and replacement of such wick. When spent, my wick may be renewed by simply unscrewing the threaded shell, or wick mounting, from the torch barrel and substituting a new wick for the spent one.

Functionally, therefore, my wick mounting and wick constitute a unit which is at once both a properly positioned wick in the torch barrel and a potential refill for a torch of corresponding size. Once applied in the torch barrel, the wick unit is to all intents and purposes fixed therein until such time as the wicking is spent and requires replacement, whereupon it is simply necessary to withdraw the quick-detachable unit from the barrel, remove the spent wick, insert a fresh one, and return the unit into the barrel. This may be done in the minimum time and with the maximum ease. The wick units, moreover, are interchangeably usable in torch barrels of corresponding size, so that any unit is a refill for all torches of identical size, and hence may be supplied independently of the torches, if desired. In contra-distinction, the plug wick must be driven-fitted in the torch barrel, and the leader must be threaded through the plug, both operations requiring the use of special fixtures, and hence the plug type of wick is wholly incapable of that speed and ease of assembly and detachment which characterizes my present invention.

The quick detachable connection of the wick mounting with the torch barrel is such as to effectively seal the upper end of the barrel against leakage of the fuel past the wick mounting, while however permitting ready insertion of the wick unit into and re-

2
moval from the barrel. Although the wick material is compressively clamped within the wick mounting to such an extent as to prevent leakage of fuel therethrough even if the torch barrel is inverted and so that the two elements constitute a unit, the wick is not compressed so tightly, however, as to prevent the free flow of fuel therethrough by capillary attraction.

10 Structurally, my wick unit may take a variety of forms. For the purposes of illustration in this application, and without thereby limiting myself to structural detail, I shall describe and show in the accompanying specification and drawings, a form of my invention which I have found satisfactory in use and well adapted to the requirements of manufacture. Throughout the specification and drawings, like reference numerals 15 are correspondingly applied, and in the drawings.

Fig. 1 is an elevation, partly in section, of a blow torch of standard type, equipped with a wick unit in accordance with my 20 invention.

Fig. 2 is a detail view of the wick unit removed from the torch barrel.

Fig. 3 is a detail view of the wick mounting or adapter, per se.

30 I have indicated at 1 the barrel, and at 2 the pressure chamber of a blow torch of standard type. The torch barrel 1 is provided at each end with an external series of screw threads 3 and 4, respectively, and the barrel ends are closed by screw caps 5 and 6, respectively, engaging said screw threads.

65 My wick unit consists of a wick mounting or adapter member, indicated generally at 7, and a length of wicking material 8. As here 70 shown, the adapted 10 is a simple shell or nipple having an external series of screw threads 9 adapted to engage in internal series of screw threads 10 cut in the upper end of the torch barrel. Below the thread series 9, the adapter is reduced, as indicated at 11, and terminating in an outwardly flared edge 12.

75 The wicking 8 is a straight length of material introduced endwise through the 80 adapter, being compressively held therein by the reduced portion 11 of the adapter. If desired, the wicking 8 may be jacketed, as indicated at 13.

85 In assembling, the wicking is drawn through the adapter and projects slightly beyond the upper end thereof so as to constitute at said end an exposed flame area disposed beneath the gas orifice 14 of the 90 goose neck 15 leading from the pressure chamber 2 of the torch. The reduced portion of the adapter compressively clamps the wicking to the adapter so that the wick and adapter constitute a unit, and the compression of the wick by said reduced portion is

sufficient to prevent leakage of fuel through the unit even though the torch be inverted, but not sufficient to prevent free flow of fuel through the wicking under the influence of capillary attraction. The degree of compression, however, is not sufficient to interfere with the free flow of the fuel in the torch barrel through the wicking.

95 By removing the upper screw cap 5, the wick unit may be inserted endwise into the torch barrel, the screw threads 9 of the adapter engaging the internal thread series 10 of the torch barrel and tightly sealing the barrel at this end so as to prevent escape of the fuel past the adapter, should the torch be inverted or laid upon its side.

100 When the wicking is spent, it may be renewed by simply removing the adapter from the barrel, drawing the spent wicking out of the adapter, substituting a fresh wicking, and replacing the adapter in the barrel. 105 The outwardly flared edge 12 of the adapter prevents the wicking from raveling and fray- 110 ing as it is drawn through the adapter.

115 My wick unit thus permits the use of straight wicks, and these wicks and their adapter mountings may be supplied in standard sizes, according to the size of the torch. The adapters and wicks are therefore interchangeably usable in torches of corresponding size, permitting a replacement 120 standardization not possible with the plug type wick, as well as a considerable saving in manufacturing cost due to the fact that I avoid the necessity for drive-fitting the wick unit in the torch barrel, as in the case 125 of the plug wick, and for threading a leader through the plug.

130 Preferably, the adapter 10 is pierced, as at 10', to provide a relief vent for the pressure within the barrel 1. This relieving vent avoids the possibility of the pressure driving the fuel up past the adapter and becoming ignited at the exposed flame area of the wicking and running down the sides of the barrel, under which circumstances the barrel 135 could not be comfortably grasped and held in the hand.

140 Although I have illustrated a construction in which the adapter is screw-threaded with in the torch barrel, my adapter and the torch barrel obviously may be provided with other forms of quick detachable connections. These, and such other modifications of structure and method as fall within the spirit 145 and scope of my invention, may all be resorted to within the limits of appended claim.

150 What I therefore claim and desire to secure by Letters Patent is:

155 A wick holder for a torch comprising a member including a tubular portion having a bore of sufficiently less cross-sectional area than the normal cross-sectional area of a

wick adapted to be held within the member, to cause part of a wick arranged within the member to be maintained sufficiently compressed to prevent leakage of fuel from the 5 torch barrel when the torch is inverted, said member also including another tubular portion having a bore of greater cross-sectional

area than the bore of said first mentioned portion and which normally receives the flame end of the wick, and means on said last mentioned tubular portion for detachably securing the member within a torch barrel.

LESTER L. LASHER.
